UNITED STATES PATENT OFFICE

158,877

SOFA

Rush Manbert, San Francisco, Calif., assignor to Specialty Manufacturing Company, San Francisco, Calif., a partnership

Application December 18, 1948, Serial No. 150,243

Term of patent 7 years

(Cl. D15—11)

To all whom it may concern:

Be it known that I, Rush Manbert, a citizen of the United States, residing in the city and county of San Francisco, State of California, have invented a new, original, and ornamental Design for a Sofa, of which the following is a specification, reference being had to the accompanying drawing, forming part hereof.

Fig. 1 is a front perspective view of a sofa showing my new design.

Fig. 2 is a plan view of the sofa shown in Fig. 1.
Fig. 3 is an end elevational view thereof.

I claim:

The ornamental design for a sofa, as shown.
RUSH MANBERT.
